UNITED STATES PATENT OFFICE

LOUIS ZWEIG, OF BROOKLYN, NEW YORK, ASSIGNOR TO SUN RISE LAMP MFG. CO., INC., A CORPORATION OF NEW YORK

DESIGN FOR A LAMP SHADE

Application filed December 27, 1929. Serial No. 33,959. Term of patent 3½ years.

To all whom it may concern:

Be it known that I, LOUIS ZWEIG, a citizen of the United States, and a resident of the city of Brooklyn, county of Kings, and State of New York, have invented a new, original, and ornamental Design for Lamp Shades, of which the following is a specification, reference being had to the accompanying drawing, forming a part hereof.

The shade is characterized by wide glass panels A which overlap the edges of the narrower glass panels B. The wider panels are provided with added raised panels C of contrasting color.

I claim:

The ornamental design for a lamp shade substantially as shown and described.

LOUIS ZWEIG.
